UNITED STATES PATENT OFFICE

2,242,937

ABSORBENT PAD

Joseph B. Biederman, Cincinnati, Ohio

Application November 30, 1939, Serial No. 306,862

1 Claim. (Cl. 128—285)

The present invention relates to absorbent pads, particularly to such pads, bandages and tampons as are used by women during their menstrual periods.

The principal object of the present invention is to provide a device such as a pad, catamenial bandage or tampon of increased absorbent capacity. In devices of the character to which this invention is directed, the absorbent properties of the device are an essential factor from which their efficiency derives, for the reason that, when a point of saturation by the menstrual or other flow is reached, the device lacks further utility and must be discarded to be replaced by a fresh one in order to prevent overflow or leakage onto the person or garments of the wearer. Such devices as are presently in use for the purposes mentioned rely upon the mechanically absorptive properties of such materials as ordinary fabrics, Cellucotton and similar materials. The present invention while employing such materials as those just mentioned as the principal element for embodying the formative structure of the device, adds thereto and increases the efficiency thereof, by including in the structure an absorbefacient material such as calcium chlorid for example or similar substance.

Further objects of the invention will appear from the following detailed description thereof.

In the drawing:

Figure 1 is a diametric sectional view of a tampon constructed in accordance with one form of this invention.

Figure 2 is a perspective illustrating the formation of a tampon in accordance with a modified form of the invention.

Figure 3 is a perspective of a catamenial pad embodying a preferred form of the invention as applied to such pads.

In the form illustrated sectionally in Figure 1, the tampon consists of a tube of absorbent material, such as Cellucotton, cotton or similar substance 1, which may be built up, of course, either of coiled laminations of the material as shown, or of a wadded mass of amorphic material. The tube 1 is provided with a hollow core 2 forming a chamber which is filled with some absorbefacient material such as calcium chlorid or substance of similar properties. In Figure 1 such substance is indicated by the numeral 3. End covers 4 for the chamber 2 are provided in order to prevent the expulsion of leakage of the ma-

terial 3 from the chamber. It is necessary of course that the substance 3 employed shall be entirely harmless when used for catamenial purposes both in its natural state or by reason of any gasses which may be liberated when the substance becomes wet. In the case of calcium chlorid it is not only harmless in its solid condition, but any gasses which it might liberate during use are mildly antiseptic and therefore beneficial to the parts when used.

In Figure 2 the tampon is modified by the inclusion of the substance 3 between the coils when forming the tampon by rolling a sheet of absorbent material 5. In this form of tampon it is of course less necessary to provide end covers 4 for the reason that the material 3 is in a plurality of thin layers and so less liable to leakage.

In Figure 3 I have shown a menstrual pad composed of laminations 6 of absorbent material such as Cellucotton, with a layer 7 of calcium chlorid or other absorbefacient material, preferably located between the lower layers of the pad. It is obvious, of course, that a plurality of layers of calcium chlorid may be provided if preferred.

In use the advantages of my new pad will be apparent. The absorbent material such as cotton or Cellucotton of course functions in the ordinary manner. By the inclusion in the internal structure of the device of calcium chlorid or similar substance of high hygroscopic properties, or even by placing thereon a quantity of such substance, the liquid constituent of the menstrual or other flow is drawn into the pad with highly increased efficiency, where the hygroscopic substance serves substantially as a reservoir increasing the absorptive capacity of the device and greatly increasing its life and efficiency. It will be apparent of course that the absorbefacient material may be incorporated in the device in numerous ways which are but modifications of my invention as above described and as covered in the appended claim.

Having thus fully described my invention, what I claim as new and desire to secure by Letters Patent is:

A tampon formed in the shape of a tube of absorbent material, a quantity of an absorbefacient substance in the opening in said tube, and absorbent plugs adapted to close the ends of said tube to retain said substance.

JOSEPH B. BIEDERMAN.
